UNITED STATES PATENT OFFICE.

HENRY T. SPERRY, OF WATERBURY, CONNECTICUT, ASSIGNOR TO THE CHASE COMPANIES INC., OF WATERBURY, CONNECTICUT, A CORPORATION.

DESIGN FOR A MINER'S LAMP.

54,787.

Specification for Design.

Patented Mar. 23, 1920.

Application filed October 28, 1919. Serial No. 334,087. Term of patent 14 years.

To all whom it may concern:

Be it known that I, HENRY T. SPERRY, a citizen of the United States, residing at Waterbury, in the county of New Haven and State of Connecticut, have invented a new, original, and ornamental Design for a Miner's Lamp, of which the following is a specification, reference being had to the accompanying drawing, forming part thereof.

The figure is a side view of a miner's lamp, showing my new design.

I claim:

The ornamental design for a miner's lamp, as shown.

HENRY T. SPERRY.

Witnesses:

JOHN SNEAGLE,
B. C. Atwood.
